CLAIM

The ornamental design for a lactation massager, as shown and described.

DESCRIPTION

FIG. 1 is a perspective view of a lactation massager showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 2.

The broken lines in the figures are for the purposes of illustrating portions of the lactation massager, which form no part of the claimed design. The additional broken lines shown in FIGS. 2 and 9 are for the purpose of showing enlarged areas, which form no part of the claimed design.
